UNITED STATES PATENT OFFICE.

LEO F. ADT, OF ALBANY, NEW YORK.

EYEGLASS-MOUNTING.

1,103,240.

Specification of Letters Patent. Patented July 14, 1914.

Application filed December 30, 1909. Serial No. 535,543.

To all whom it may concern:

Be it known that I, Leo F. Adt, of the city of Albany, in the county of Albany and State of New York, have invented certain new and useful Improvements in Eyeglass-Mountings; and I do hereby declare the following to be a full, clear, and exact description of the same, reference being had to the accompanying drawings, forming a part of this specification, and to the reference-numbers marked thereon.

My present invention relates to eyeglass mountings and more particularly to the type in which the guards are positioned or moved toward the nose by resilient means, such as springs, and are moved away from the nose by operating portions, such as finger pieces, the object of this invention being to provide an inconspicuous construction which is capable of being adapted to the noses of different individuals.

A further object of the invention is to produce a mounting of simple construction and one that may be manipulated with convenience during assembling, adjustment, or repair.

To these and other ends the invention consists in certain improvements and combinations of parts all as will be hereinafter more fully described, the novel features being pointed out in the claims at the end of the specification.

In the drawings: Figure 1 shows, in enlarged elevation, an eyeglass mounting constructed in accordance with the present improvements, one of the guards and its spring being removed; Fig. 2 is a top plan view of the same parts; Fig. 3 is a bottom plan view with a portion of the remaining guard broken away; Fig. 4 is a central transverse section through the mounting.

In the embodiment of the invention herein shown the lenses A are connected by a support which preferably comprises an arched or bridged portion 1 for straddling the nose, lens attaching devices or mounts 2 for securing the lenses A and connecting portions 3 between the bridging portion and the lens attaching devices. The connecting portions are in this instance in the form of horizontal loops of pliable material arranged in the rear of the plane of the lenses and permitting the adjustment of the lenses relatively to the bridging portion for different pupillary distances. In order to support the guards, brackets 4 are preferably

extended from the bridging portion 1 and lie between the ends of the latter and the proximate lens attaching devices, in advance of the adjustable or pliable loops 3, the upper surfaces of the brackets forming horizontal seats 5 for the nose guards, and having bearings or pivots 6 extending upwardly therefrom, with heads 7 at their upper ends to coöperate with the upper surface of the guards. Each guard, in this instance, is formed from a single piece of flat stock and embodies a lever portion 8 provided at its forward end with an outwardly extending finger piece 9 connected thereto by downward or vertical bend 10, and also provided at its rear end with a nose engaging member 14 preferably having upper and lower nose engaging pads or surfaces of any suitable or desired type. The particular form of nose engaging member and its formation with respect to the guard lever, and their connection constitutes the subject matter of a divisional application Serial No. 709,208, filed July 18, 1912, and need therefore not be described herein. Each guard turns above the support upon its bearing or pivot 6, the lever 8 being provided in one edge with a laterally opening bearing recess 15 permitting the guard to be attached to or separated from the mounting by a lateral movement, and in order to strengthen the lever in proximity to the recess the opposite edge of said lever is bent upwardly to provide a longitudinally extending flange 16 opposite said recess. The springs for positioning the guards in this instance, are located upon the under side of the support and may each embody a coiled portion 17 offset to one side, preferably the rear side of the turning axis of the guard, and having an end 18 extending forwardly and entering a securing device in the present form of a socket 19 horizontally arranged preferably in approximately the plane of the lenses on the under side of the support but facing or opening transversely of said plane; the other end of the spring being in the form of a forwardly extending arm 20 engaging the guard on the other side or in front of its turning axis, the guard preferably having an eye 21 beyond the bend 10 on the rear side of its finger piece 9 to receive a hook 22 on the free end of the spring arm.

In order to remove the mounting from the nose of the wearer or to place it upon the

- nose, the finger pieces 9 are pressed toward each other, thus separating the nose engaging portions 14 of the guards. After the desired positions of the guards have been reached, the finger pieces 9 are released, thus permitting the nose engaging members to move inwardly under the action of their springs. The springs act on the guards in directions to retain the bearing recesses 15 in engagement with the bearing members 6, and in order to detach the guards it is merely necessary to move the free ends of the springs inwardly out of the eyes 21 when the levers may be moved inwardly from beneath the heads or overhanging portions 7. The springs remain on the mountings when the guards are removed and may be removed therefrom by withdrawing the ends 18 from the sockets 19.
- 20 An eyeglass mounting constructed in accordance with this invention is inconspicuous when upon the wearer. The springs are so located that only small portions thereof are visible from the front or top of the mounting, while they are, at the same time, of such length as to give sufficient pressure upon the nose of the wearer. The connection of the springs to the mounting permits the ready disconnection or attachment of the parts without the use of separate fastening devices that are liable to become lost or mislaid.
- In the claims:
1. In an eyeglass mounting, the combination with a support, a pivot and a finger piece guard lever mounted to swing thereon and to extend from front to rear of the support, of a spring for positioning the guard embodying two arms extending in substantially parallel relation transversely of the plane of the lenses and connected together by a portion located on one side only of the pivotal axis, permitting the removal of the spring in a direction transverse to the said axis and to the pivot, said spring arms having their free ends detachably connected to the guard and support respectively, the connection with the guard being at a point on the opposite side of the pivotal axes thereof.
  - 50 2. An eyeglass mounting comprising a support for the lenses, a guard mounted to swing on one side of the support, a spring securing device arranged on the other side of the support in the plane of the lenses, and a spring for the guard comprising an end secured by said device, a coil arranged to one side of the turning axis of the guard and an arm extending to the other side of the turning axis of the guard and coöperating with 60 the latter.
  3. An eyeglass mounting comprising a support for the lenses, a socket horizontally arranged on one side of the support with its axis transverse to the plane of the lenses, a guard mounted to swing on the opposite side of the support, and a spring for the guard comprising an end secured in the socket, and an arm extending to one side of the socket and connected to the guard.
  4. An eyeglass mounting comprising a support for the lenses, a guard mounted to swing on the upper side of the support, a socket arranged horizontally on the under side of the support, and a spring comprising an end fitted in the socket, a coil on one side of the turning axis of the guard, and an arm extending to the other side of the turning axis and secured to the guard.
  5. An eyeglass mounting comprising a support for the lenses, a nose guard arranged above the support, coöperative bearing members on the guard and the support, separable by an inward movement of the guard, a socket arranged horizontally on the under side of the support, with its axis transverse to the plane of the lenses, and a spring for the guard comprising an end secured in the socket, a coiled portion in the rear, and a spring arm coöperating with the guard forwardly of the turning axis of the latter, and acting in a direction to hold the bearing members in engagement.
  6. In an eyeglass mounting, the combination with a support, a pivot and a guard lever mounted to swing on the support, of a spring for positioning the guard having one end acting against the latter and the other against the support and provided with an intermediate loop or coil arranged independently of the pivot to one side of the pivotal axis of the lever and means for securing one end of the spring to one of said first mentioned members comprising a box or socket on one part located to one side of the loop or coil but substantially in the same plane therewith into which socket the other part extends.
  7. An eyeglass mounting comprising a support for the lenses, a nose guard mounted to swing above the support, having a lever turned downwardly in front of the support, an eye arranged on the rear face of the downwardly turned portion, and a spring for the guard having a forwardly extending arm engaging said eye.
